OUTBOARD MOTOR CONSTRUCTION

Marshall A. Blu, Chicago, Frank M. Morgan, Glen Ellyn, and Lawrence E. Dempsey, Oak Park, Ill., assignors to Sears Roebuck and Co., Chicago, Ill., a corporation of New York

Application December 10, 1936, Serial No. 115,096

6 Claims. (Cl. 123—195)

The invention relates to improvements in outboard motor construction.

One object of the invention is to provide an improved outboard motor structure in which the power unit or engine, and its accessories are arranged in a compact assembly with all manual controls grouped at a central control point for convenient access, and in which the engine and associated parts are enclosed to provide an attractive, streamlined appearance.

Another object is to provide an improved fuel tank support and engine enclosing structure for outboard motors in which the parts are assembled in a compact, rigid unit capable of being quickly and easily assembled with the other elements of the motor and adapted to be readily detached therefrom for repair or replacement.

Another object is to provide an improved fuel tank system for outboard motors.

Still another object is to provide improved means for enclosing the control mechanism of outboard motors whereby the mechanism is effectively protected and the general appearance of the motor is improved by reason of the control elements being concealed.

A further object is to provide improved means for controlling the ignition system of an outboard motor.

It is also an object of the invention to improve and simplify the construction and arrangement of the individual parts of the motor structure with a view of facilitating manufacture and assembly of the same, and providing an outboard motor which is efficient and reliable in operation, which is well balanced and attractive in appearance, and which can be manufactured at a relatively low cost.

Other objects and advantages of the invention will become apparent from the following detailed description of the preferred embodiment disclosed in the accompanying drawings. It will be understood, however, that various changes in form, construction and arrangement of the parts may be made by those skilled in the art without departing from the spirit and scope of the invention as expressed in the appended claims.

Referring to the drawings:

Figure 1 is a vertical sectional view of an outboard motor embodying the features of the invention.

Fig. 2 is a sectional view taken along the line 2—2 of Fig. 1.

Fig. 3 is a sectional view taken along the line 3—3 of Fig. 1.

Fig. 4 is an elevational view of the upper part

of the motor with the shielding structure broken away to show the arrangement of the fuel supply and ignition control means.

Fig. 5 is a front elevation of the upper part of the motor.

Fig. 6 is a rear elevation of the upper part of the motor.

Fig. 7 is a plan view of the motor with a part of the shielding structure broken away to show the fuel tank support.

Fig. 8 is a sectional view taken along the line 8—8 of Fig. 1.

Fig. 9 is a sectional view taken along the line 9—9 of Fig. 4.

Referring to Fig. 1 of the drawings, the outboard motor selected to illustrate the invention comprises a water cooled, two-cycle internal combustion engine having a crank case 10 and a cylinder 11 mounted in a horizontal position on the upper end of a vertical drive shaft housing 12. The crank case 10 is in the form of a unitary casting and is provided with upper and lower bearings 13 and 14 for supporting a crank shaft 15 in a generally vertical position. A piston 16 operating in the cylinder 11 is arranged to drive the crank shaft through the medium of a connecting rod 17.

Mounted on the projecting upper end of the crank shaft 15 is a suitable flywheel 18 to which is bolted a starting plate 19 of conventional construction. A vertical drive shaft 20 is keyed to the lower end of the crank shaft and extends through the housing 12 to a suitable propeller gear housing 21 carried on the lower end of the drive shaft housing. The gear housing 21 encloses conventional gear mechanism for drivingly connecting the shaft 20 with a propeller 22 and a water pump 23. The gear housing also supports a suitable anti-cavitation plate 24.

As shown in Fig. 1, the drive shaft housing 12 comprises an upper section 25 in the form of a hollow casting and a streamlined tubular lower section 26 (Figs. 2 and 3) connecting the section 25 with the propeller gear housing 21. The upper section 25 is adapted to be bolted or otherwise rigidly secured to the cylinder and crank case assembly and is arranged to communicate with the interior of the cylinder 11 through an exhaust port 27 in the cylinder casting as shown in Figs. 1 and 8. The exhaust gases from the cylinder are thus conveyed through the shaft housing and discharged through an opening 28 in the tubular section 26, the opening preferably being at a point below the water line to muffle the exhaust noise. The casing section 25 is also

formed with a tubular passage 29 communicating with the water jacket 30 of the cylinder 11. Water from the pump 23 is carried by a pipe 31 and the passage 29 to the water jacket 30 and, after circulating therein, is discharged through an outlet 32 at the rear of the cylinder casting.

A suitable swivel bracket 33 for supporting the motor assembly in operating position on the gunwale or other part of a boat is rotatably mounted on the housing section 25 by means of a sleeve member 34 engaging in a channel-shaped bearing 35 formed on the housing section. An abutment block 36 on the bracket engages an annular bearing surface 36^a formed on the lower portion of the housing section to hold the motor assembly rigid with the bracket.

Fuel and air mixture for operating the internal combustion engine is supplied to the cylinder 11 by a carburetor or mixing valve 40 (Figs. 1 and 4) mounted on the forward end of the crank case 10 and communicating therewith through a port 41. The mixing valve may be of any preferred construction and, as herein shown, comprises the usual lift member 42 normally closing the air and fuel ports and adapted to be raised by suction created by the piston on its compression stroke to admit fuel and air to the crank case. The fuel and air mixture thus drawn into the crank case in one stroke of the piston is compressed in the next working stroke thereof and the compressed mixture is discharged into the cylinder through an intake port 43 which is uncovered by the piston as it approaches the end of its working stroke. The lifting member 42 may be raised manually by means of the stem 42^a to facilitate starting of the engine.

A needle valve 44 of any suitable construction controls the flow of the fuel to the mixing valve. Adjustment of the needle valve is effected by means of a rotatable member having a knob 45 arranged in a conveniently accessible position at the forward end of the motor structure. As shown in Fig. 5, the knob may be formed with a peripheral flange 46 graduated to provide a visual indication of the valve setting.

Fuel is fed to the mixing valve 44 by gravity from suitable tanks 47 and 48 mounted on the upper part of the motor structure and preferably located on opposite sides of the engine to provide a well balanced assembly as shown in Fig. 4. While tanks of any suitable shape and construction may be used, it is preferred to employ a streamlined tank of generally ellipsoidal or tear drop form, having a relatively blunt forward end and an elongated tapering rear end as shown in Fig. 7. Such tanks provide ample fuel storage capacity in a comparatively small space and materially improve the appearance of the motor.

The tanks 47 and 48 are connected by a feed line 49 in which is interposed a T-fitting 50 connecting the line with the needle valve 40. Thus the feed line in addition to delivering fuel from the tanks to the engine serves to equalize the fuel between the two tanks. With this construction only one of the tanks need be provided with an opening for filling purposes while the other tank requires only a small opening for admitting air to and from the tank to equalize the pressure therein. As herein shown the filling opening is provided in the tank 47, the body of the tank being struck outwardly to form an upwardly projecting flange 51 for this purpose. A corresponding flange 52 on the tank 48 provides an air open-

ing for this tank. The openings may be closed by the usual vented screw caps 53 and 54, respectively.

The fuel tanks and their supporting structure are preferably constructed and arranged so that they may be assembled with or detached from the motor structure as a unit. To this end, each of the tanks is provided with an outwardly projecting flange 55 brazed or otherwise rigidly secured to the inner side wall, as shown in Figs. 4 and 7. 10 These flanges are secured by suitable means such as bolts 56 to opposite side edges of a rectangular supporting plate 57 which, in turn, is adapted to be removably secured to the cylinder and crank case castings as by bolts 58. 15

As shown in Fig. 7, the supporting plate 57 is formed with a generally rectangular aperture 59 for receiving the upper part of the crank case 10 and the crank shaft bearing 13. The plate is of sufficient width to project laterally slightly beyond the rim of the flywheel 18 so that the fuel tanks 47 and 48 are held closely adjacent thereto and extend longitudinally of the cylinder and crank case assembly. 20

A member 60 secured between the fuel tanks 47 and 48 provides additional rigidity to the tank assembly and serves to enclose the upper part of the engine and its accessories. The member 60 may be of any suitable shape and construction and, as herein shown, is formed with a slight convex curvature as viewed in longitudinal section. The rearward end of the member may be rolled downwardly and inwardly as shown in Fig. 1 to avoid leaving a sharp exposed edge and to secure lateral rigidity. The member 60 terminates at its forward end in a generally rounded downwardly projecting flange portion 61 to which is secured a front cover plate 62. The cover plate 62 extends downwardly and then rearwardly to the underside of the crank case 10 to which it is removably secured by bolts 62^a thus comprising, with the member 60, a casing structure for enclosing engine accessories and control devices as will appear presently. A beaded aperture 63 in the member 60 permits the flywheel 18 to project therethrough. 35

To avoid any possibility of injury to the fuel tanks or engine cylinder when the motor is placed in a reclining position, legs 64 are bolted to opposite side edges of the supporting plate 57 and 50 arranged to extend rearwardly beyond the end of the tanks and cylinder. The legs thus rest on the floor or other surface and, with the supporting plate, carry the weight of the motor. A transverse member 65 brazed or otherwise rigidly secured to the fuel tanks 47 and 48 at points closely adjacent the rear edge of the supporting plate stiffens the entire tank structure and prevents the supporting plate from bending under the weight of the motor. 60

In accordance with the usual practice, the engine of the outboard motor is provided with electrical means in the form of a spark plug 66 for igniting the fuel and air mixture in the cylinder 11. While a battery and spark coil may be employed for supplying high tension current to the spark plug, the preferred construction contemplates the use of a flywheel type magneto of well known construction for this purpose. In magneto's of this type, the flywheel 18 of the engine 70 is provided with a series of permanent field magnets 67 arranged to cooperate with stationary armature coils 68, as shown in Fig. 4. 65

The firing time of the engine is ordinarily regulated by shifting an adjusting member arranged 75

to vary the timing of the spark. When magneto ignition is employed, the adjustment is effected by varying the position of the armature coils 68 relative to the axis of the flywheel. To this end, 5 the coils are mounted on the adjusting member which is in the form of a generally circular plate 69 having a centrally disposed bearing 70 for supporting the member loosely on the hub of the crank shaft bearing 13 concentric with the fly- 10 wheel 18. A flexible conductor 71 connects the armature coils with the spark plug 66.

Suitable manually operable control means conveniently accessible at the front of the motor structure is provided for rotating the magneto 15 adjusting member 69 to regulate the timing of the engine. In its preferred form, the control means comprises a tubular control member 72 rotatably supported on a substantially horizontal axis perpendicular to the axis of the crank shaft 20 15 and drivingly connected with the adjusting member. Support for the member is provided by a rear bearing 73 carried on a bracket 73^a (Fig. 9) on the forward end of the crank case casting 10 and a front bearing formed by a down- 25 wardly bent section 57^a at the forward end of the fuel tank supporting plate 51.

The driving connection between the control member 72 and the adjusting member 69 preferably comprises a pinion 74 rigidly secured to 30 the control member as by a set screw 75 and adapted to mesh with a gear sector 76 carried by the adjusting member. Thus, by rotating the control member 72, the position of the adjusting member 69 and armature coils 68 mounted 35 thereon may be varied as required to obtain efficient operation of the engine. Rearward longitudinal movement of the control member is prevented by the pinion 74 engaging the end of the bearing 73 while movement of the member in the other direction is limited by a spring 77 interposed between the end of the bearing 73 and a nut 78 threaded onto the inner end of the member. A locknut 79 prevents the first mentioned nut from working loose due to vibration of the engine. 40

The control member 72 is arranged to project 45 forwardly beyond the casing structure 62 above and closely adjacent the valve adjusting knob 45. A lever or handle 80 fast on the projecting end of the member provides a convenient means for manually rotating the member. As herein shown, the handle 80 is formed with a radially projecting tip 81 constituting a pointer for co-operating with a graduated scale 82 to give a visual indication of the magneto setting. The 50 55 scale may be formed integral with or suitably secured to the casing 62.

Means is also provided for short circuiting or grounding the magneto to interrupt the supply of high tension current to the spark plug 66 and thus stop the engine. As herein shown, this means comprises a suitable grounding switch having a stationary contact 83 electrically connected with the magneto armature coil and a movable contact 84 grounded on the frame of the 55 motor. The contact 83 may be conveniently mounted on the crank case 10 and insulated therefrom by a suitable electrical insulator 85. The contact 84 is mounted on the inner end of a cylindrical rod 86 slidably supported for end- 60 wise movement within the tubular control member 72. The rod 86 is formed with an enlarged end portion 87 and a compression spring 88 interposed between this enlarged end portion and a shoulder formed on the interior wall of the control member tends to maintain the rod in a for- 75

ward or switch opening position. With the rod in this position, the end portion projects forwardly beyond the end of the control member and the handle 80 and constitutes a stop button by which the rod may be shifted manually into 5 switch closing position to stop the motor.

It will be observed that the various control devices including the magneto adjusting lever or handle 80, the stop button 81, the needle valve adjusting knob 45, and the mixing valve stem or 10 choke member 42^a are all conveniently grouped at the forward end of the motor structure on a control panel provided by the cover plate 62. The controls are therefore readily accessible to the operator. Moreover, the cover plate 15 constitutes a casing structure which effectually covers and conceals the control mechanism, thereby preventing the operator from coming into contact therewith.

It will be apparent from the foregoing that the 20 invention provides an improved outboard motor structure in which the engine and its accessories are arranged in a compact, attractively appearing assembly with the various elements effectively enclosed to present an attractive streamlined appearance. The fuel tanks, enclosing structure and their supporting means are assembled in a compact, rigid unit which can be quickly and easily assembled with the motor structure and can be readily detached therefrom for repair or 25 replacement. The fuel storage system embodies a plurality of tanks interconnected for operation as a unit and arranged in a manner such as to improve the general appearance of the motor. Efficient and practical control means is provided 30 for adjusting the magneto to obtain proper timing of the motor under varying operating conditions. Moreover, control of the motor is materially simplified by grouping all controls in closely adjacent relation on the forward end of the motor structure where they are conveniently accessible to the operator. 35 40

We claim as our invention:

1. An outboard motor structure comprising, in combination, an internal combustion engine, a 45 unitary fuel tank structure including a pair of streamlined fuel tanks each having an outwardly projecting longitudinal flange extending along one side thereof, a rectangular plate adapted to be removably secured at opposite sides to the 50 flanges of the respective tanks to support the tanks in spaced relation, a tubular member extending between the tanks and rigidly secured thereto at opposite ends to provide additional rigidity for the structure, an engine enclosing 55 member extending between said tanks and rigidly secured thereto at points spaced substantially above said flanges and said tubular members, and means for removably securing said plate to said engine to support the tank structure thereon as 60 a unit.

2. An outboard motor structure comprising, in combination, an internal combustion engine, a pair of ellipsoidal fuel tanks for supplying fuel to said engine, and means supporting said tanks 65 on said engine, said supporting means including a rectangular supporting plate removably secured to the top of said engine in a generally horizontal position and arranged to project on opposite sides of the engine, an outwardly projecting longitudinal flange on each of said tanks, and means for detachably securing the flanges of the respective tanks to the projecting portions 70 of said member to support the tanks on said engine.

3. An outboard motor structure comprising, in combination, an internal combustion engine, a pair of fuel tanks for supplying fuel to said engine, and means supporting said tanks on opposite sides of said motor, said supporting means including a rectangular plate extending across and removably secured to said engine, and means rigidly securing said tanks to opposite sides of said plate.
- 10 4. An outboard motor structure comprising, in combination, an internal combustion engine having horizontally disposed cylinder means mounted on the upper end of a vertical drive shaft housing, fuel tanks for supplying fuel to said engine, means supporting said tanks on said engine, and a pair of spaced legs mounted on said supporting means and extending rearwardly of said cylinder means for supporting the weight of the engine and protecting said cylinder and 15 said tanks when the motor structure is disposed in a horizontal position.
- 15 5. An outboard motor structure comprising, in combination, an internal combustion engine, a

pair of fuel tanks for supplying fuel to said engine, a rectangular plate detachably secured to the top of said engine in a generally horizontal position, the tanks being secured to opposite side edges of said plate, and an engine-housing member spaced above said plate and rigidly secured to said tanks, said plate said housing member and said tanks being removable as a unit by detaching said plate from said engine.

6. An outboard motor structure comprising, in combination, an internal combustion engine, and a unitary fuel tank structure comprising a pair of elongated fuel tanks in laterally spaced relation, and a pair of vertically spaced plates attached at their side edges to the respective tanks, 15 the upper plate constituting a housing member and the lower plate being detachably secured to the top of the engine, the tank structure being removable as a unit upon detachment of the lower plate from the engine.
